(57) **CLAIM**

The ornamental design for a cologne and perfume bottle, as shown and described.

DESCRIPTION

FIG. 1 is a front right perspective view illustrating our new design for a cologne and perfume bottle;

FIG. 2 is a back view thereof;

FIG. 3 is a left side view thereof;

FIG. 4 is a right side view thereof;

FIG. 5 is a top view thereof;

FIG. 6 is a bottom view thereof; and,

FIG. 7 is a perspective, exploded view showing two components of the cologne and perfume bottle with the broken lines showing, for illustrative purposes only, how the two components are connected to each other.
